UNITED STATES PATENT OFFICE.

EUGENE KAUFMANN, OF NEW YORK, N. Y.

DESIGN FOR A HORN.

46,502.

Specification for Design.

Patented Oct. 6, 1914.

Application filed July 30, 1914. Serial No. 854,186. Term of patent 7 years.

To all whom it may concern:

Be it known that I, EUGENE KAUFMANN, a citizen of the United States, residing at New York, borough of Manhattan, in the county and State of New York, have invented a new, original, and ornamental Design for a Horn, of which the following is a specification, reference being had to the accompanying drawing, forming part thereof.

The figure is a perspective view of a horn illustrating my new design.

I claim:

The ornamental design for a horn as illustrated.

EUGENE KAUFMANN.
